UNITED STATES PATENT OFFICE.

ALBERT J. WEISS, OF NEW YORK, N. Y.

HEATING-STOVE.

SPECIFICATION forming part of Letters Patent No. 308,222, dated November 18, 1884.

Application filed June 9, 1883. (No model.)

To all whom it may concern:

Be it known that I, ALBERT J. WEISS, a subject of the King of Prussia, residing at New York, in the county and State of New York, United States of America, have invented certain new and useful Improvements in Heating-Stoves, of which the following is a specification sufficiently full, clear, and exact to enable others skilled in the art to make and use the same, reference being had to the accompanying drawings, forming a part thereof.

The object of the invention is to secure economy of fuel; and to this end it consists of a stove of peculiar construction, as hereinafter described and claimed, whereby a thorough or approximately complete combustion of the fuel is attained.

In the accompanying drawings, Figure 1 is a front elevation of this improved stove. Fig. 2 is a vertical central section on line $x-x$, Fig. 1. Fig. 3 is a vertical central section on line $y-y$, Fig. 2. Fig. 4 is a transverse section on line $z-z$, Fig. 2. Fig. 5 is a transverse section on line $w-w$, Fig. 2. Fig. 6 is a transverse section on line $v-v$, Fig. 2. Fig. 7 is a transverse section on line $u-u$, Fig. 2. Fig. 8 is a transverse section on line $t-t$, Fig. 2. Fig. 9 is a transverse section on line $s-s$, Fig. 2.

Similar letters of reference indicate corresponding parts in the different figures.

The fire-pot of this stove is provided with a closed top, g , a side opening, s' , for the supply of fuel through the door s , a grate, d , at its bottom, and a grated opening, e , on the rear side near its top. Below the fire-pot is an ash-pot, q , provided with a door, p . An outer case or shell, c , of larger diameter than the fire-pot b , surrounds the latter, forming an annular flue-space, a , between said fire-pot and casing. Arranged a short distance above the fire-pot is a horizontal plate, h , which forms with the top plate of the fire-pot a horizontal flue, h' . The top plate of the fire-pot extends to the outer casing of the stove and closes the annular flue-space a , excepting the segmental opening at the front of the stove, which forms a communication between said flue-space a and the horizontal flue h' . A horizontal segmental plate, k , above the plate h , forms with said plate a short horizontal flue, h^2 , said plate h having an opening at the rear of the stove, through which communication is effected between the

backward horizontal flue h' and the return horizontal flue h^2 . A vertical plate, n , extends from the front edge of the horizontal plate k 55 upward to near the top of the stove, forming with the upper casing or dome, m , a vertical flue at the front of the stove, which communicates with the horizontal flue h^2 . A vertical plate, o , extends downward from the 60 top of the stove to near the horizontal plate k , and forms with the plate n a central downward flue, l' , and with the rear portion of the casing or dome m an upward flue, l^2 . The flue l' communicates at the top of the stove with 65 the flue l and above the plate k with the flue l^2 , with which latter the escape-pipe is connected near the top of the stove. The doors s and p are preferably so constructed as to be rendered air-tight after the gases have been 70 consumed.

The operation is as follows: The fire-pot being filled with anthracite coal or other suitable fuel and the fire started, the top plate and sides will become highly heated or red-hot. 75 The gases of combustion will escape from the fire-pot through the opening e into the annular space a , and thence pass around the fire-pot in contact with the heated sides thereof to the front of the stove, thence upward through the 80 segmental opening into the horizontal flue h' , over the heated top of the fire-pot to the rear of the stove, thence upward into the horizontal flue h^2 , and forward again to the vertical flue l , thence upward through said flue to the top of the stove, 85 thence downward through the central flue, l' , thence upward through the flue l^2 to the smoke-pipe. The gases thus impinge against the red-hot side and top of the fire-pot, having long continuous contact therewith, whereby the 90 gases are thoroughly consumed.

The arrangement of flues in the upper portion or dome of the stove forms a very extended radiating-surface.

I am aware that a stove the fire-pot of which 95 has a closed top and a side opening communicating with a vertical flue is not new; but in that case the products of the gases are conducted immediately away from the fire-pot, and the advantages secured by the arrangement of horizontal flues, as in my invention, are not obtained.

I claim as my invention and desire to secure by Letters Patent—

1. An improvement in a stove, consisting of a fire-box having a closed top or closely-fitting cover, a grated opening in one side of the fire-box, a shell inclosing the fire-box, an annular flue between the fire-box and shell, and a horizontal flue at the top of the fire-box.

2. As an improvement in stoves, the combination of a fire-box, *b*, having a closely-covered top, *g*, an annular flue, *a*, surrounding the fire-box, a horizontal flue over the top of the fire-box, a second horizontal flue immediately above the first horizontal flue and com-

municating therewith, and a vertical flue communicating with said second horizontal flue.

3. A fire-box having a covered top and surrounding annular flue and the horizontal flue on the top of the fire-box, in combination with the plate *h* and the flues *l*, *l'*, and *l''*, substantially as described. 15

ALBERT J. WEISS.
